Des. 226,093
Patented Jan. 23, 1973

226,093

PORTABLE TRANSMITTER-RECEIVER

John V. Whiting, Carrier 5, Andrews Drive, Altamonte Springs, Fla. 32701, and Gene T. Brown, 1746 Oakmont Lane, Orlando, Fla. 32804

Filed Nov. 19, 1971, Ser. No. 200,661

Term of patent 14 years

Int. Cl. D14—03

U.S. Cl. D26—14

FIG.1

Des. 226,093

PAGE 2

FIG. 2

FIG. 3

FIG. 4

FIG. 5

FIG. 6

FIG. 7

FIG. 1 is a perspective view of the transmitter-receiver showing our new design;

FIG. 2 is a front elevation view of the design shown in FIG. 1;

FIG. 3 is a rear elevation view of the design shown in FIG. 1;

FIGS. 4 and 5 are opposite side elevation views of the design shown in FIG. 1; and

FIGS. 6 and 7 are top and bottom views respectively of the design shown in FIG. 1.

We claim:

The ornamental design for a portable transmitter-receiver, as shown and described.
